(57) **CLAIM**

The ornamental design for a prism of sensor chip for biochemical analysis, as shown and described.

DESCRIPTION

FIG. 1 is a perspective view of a prism of sensor chip for biochemical analysis, showing our new design;

FIG. 2 is a side elevational view thereof;

FIG. 3 is a side elevational view thereof from the side opposite that shown in FIG. 2;

FIG. 4 is a top plan view thereof;

FIG. 5 is a bottom plan view thereof;

FIG. 6 is a side elevational view thereof from the left of FIG. 2; and,

FIG. 7 is a side elevational view thereof from the right of FIG. 2.

The broken line representation indicates environmental structure and is not claimed in this application.
